EARTH BORING TOOL

Filed Nov. 17, 1930

UNITED STATES PATENT OFFICE

LUTHER STROSNIDER, OF ONAGA, KANSAS, ASSIGNOR OF ONE-FOURTH TO J. M. EVERTS, OF CENTRALIA, KANSAS, ONE-FOURTH TO EDWARD MILLER, OF ONAGA, KANSAS, AND ONE-FOURTH TO H. A. GRUTZMACHER, OF ONAGA, KANSAS

EARTH BORING TOOL

Application filed November 17, 1930. Serial No. 496,221.

This invention relates to a tool designed primarily for boring small holes in hard earth or soft rock. It is especially advantageous as a means for boring holes used for holding explosives in blasting stumps, soft rock, earth banks, and the like.

It is an object of the invention to provide a tool of simple and inexpensive construction which will not only cut into the dirt or rock in the same manner as an auger but will also slightly ream the hole to gradually enlarge it as the tool enters or advances.

Another object is to provide a tool of this character which is of sturdy construction utilizing blades which can be sharpened readily and which are duplicates.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed without departing from the spirit of the invention.

In the accompanying drawing, the preferred form of the invention has been shown.

In said drawing:

Figure 1 is a front elevation of the tool, a portion of the shank being broken away.

Figure 2 is a side elevation.

Figure 3 is an end elevation.

Figure 4 is a section on line 4-4, Figure 2.

Figure 5 is a section on line 5-5, Figure 2.

Referring to the figures by characters of reference, 1 designates the shank of the tool which can be of any desired length and is formed preferably of pipe. To one end of the shank is secured a handle or grip 2 while the other end is extended between the transversely bowed attaching ends or faces 3 of the blades of the tool.

As before stated the blades forming a part of the tool are duplicates. The blades are oppositely disposed and the description of one will apply to both. Each blade includes an intermediate cutting portion which is straight from end to end and merges at its upper end along a curved line into the at-

taching portion 3 as indicated at 5. The lower portion of each blade is curved laterally as shown at 6 and the straight cutting or advancing edge 7 of the portion 4 merges into a curved cutting edge 8 which extends to a point 9 at the end of the blade.

The curved pointed end portions 6 of the two blades are crossed as indicated at 10 and that portion of the back edge of each curved end 6 which projects below the opposed curved portion 6 is beveled to a cutting edge 11. This cutting edge extends to the point 9.

That portion of the back edge and each of the curved parts 6 located above the point of crossing indicated at 10 is blunt as shown at 12.

The two blades 4 are bowed transversely and are tapered downwardly to a slight extent toward their point of crossing. The straight cutting edge 7 of each blade is pitched at a slight angle relative to the shank 1. The two blades are connected adjacent to their point of crossing by a tie pin 13 which is secured in the blades by upsetting the ends thereof as shown at 14.

In practice the points 9 are thrust against the hard earth or soft rock at the point where a hole is to be bored. The tool is then rotated about its longitudinal axis and the points will dig into the surface and loosen the material which will be deflected upwardly along the curved portions 6 into the space between blades 4. The advancing curved cutting edge 8 will act with a shearing effect of the material being bored and as the blades 4 diverge toward the shank 1 the straight cutting edges 7 will act to gradually ream the bore so as to enlarge it and permit free movement of the cut material upwardly between the blades and toward the shank 1.

When the tie pin 13 is in position it binds the two blades at their point of crossing, each of the blades being notched as clearly shown in Figures 1 and 3 so that they will interfit.

Each blade is a duplicate of the other and the cost of production is thus greatly reduced.

The blades can be of any desired length.

It has been found in practice that by providing a tool such as herein described a bore can be quickly produced in hard earth or soft

rock so that the structure is thus particularly adapted for producing holes where blasting is to be done under certain conditions.

After a certain amount of cut material has accumulated between the blades 4 the tool can be withdrawn, the cut material dislodged therefrom, and the tool then reinserted and actuated.

What is claimed is:

- 10 A boring tool of the class described including a rotatable shank, separate opposed elongated blades secured thereto, each blade being bowed transversely and having its free end portion extending to a point, said blades
- 15 being crossed and in contact adjacent to their points and converging gradually to their point of crossing, the free ends of the blades diverging from their point of crossing, all portions of the advancing edge of each blade
- 20 from the point to the shank being disposed in the same plane, the planes occupied by the advancing edges of the two blades diverging from the shank, and a tie pin connecting the blades above and binding them together at their point of crossing.
- 25

In testimony that I claim the foregoing as my own, I have hereto affixed my signature.

LUTHER STROSNIDER.
